WILLIAM L. MARDEN, OF NEW YORK, N. Y., ASSIGNOR TO NEPTUNE METER COMPANY, OF NEW YORK, N. Y., A CORPORATION OF NEW JERSEY.

REGISTER FOR WATER-METERS, &c.

1,397,534.

Specification of Letters Patent.

Patented Nov. 22, 1921.

Application filed September 30, 1920. Serial No. 413,777.

To all whom it may concern:

Be it known that I, WILLIAM L. MARDEN, a citizen of the United States, residing in the borough of Manhattan, of the city of New York, in the State of New York, have invented certain new and useful Improvements in Registers for Water-Meters, &c., of which the following is a specification, reference being had to the accompanying drawings, forming a part hereof.

This invention relates to registers for use in connection with water meters and for other like purposes in which the actuating means operate through a clock train, pointers or indicators usually being carried by the shafts or certain of the shafts of the clock train for coöperation with dials depicted on the dial plate. The shafts of the clock train are usually mounted in parallel plates of metal which are held in proper spaced relation by posts and screws, while the dial plate, usually enameled and therefore expensive and also liable to fracture of the enamel by pressure, is secured by screws to one of the gear supporting plates. The number of screws and nuts required, with the coacting threaded parts, makes the total number of parts which enter into the construction of the supporting frame very large and somewhat expensive and also makes the labor of assembling considerable. It is the object of this invention to improve the construction of the supporting frame of the gear train in such a manner as to reduce very largely the number of parts required, to reduce the cost of production of such parts and to facilitate the work of assembling the clock train and the frame, as well as to provide means for holding the enameled dial plate in position which shall avoid the danger of fracture of the enamel by the pressure of screw heads. The invention will be more fully explained hereinafter with reference to the accompanying drawing in which it is illustrated and in which—

Figure 1 is a view partly in vertical central section and partly in elevation showing the upper part of a water meter of ordinary construction with the clock train of the register supported in a frame which embodies the invention.

Fig. 2 is a view of the under side of the lower member of the supporting frame.

Figs. 3 and 4 are detail views in section

on the planes indicated by the broken lines 55 3—3 and 4—4 respectively of Fig. 2, but on a larger scale.

Figs. 5, 6 and 7 are views showing details of construction to be described.

The upper part of the frame or casing of 60 a water meter of ordinary construction and operation is indicated at *a* in Fig. 1 and on this is mounted the casing *b* which incloses the clock train *c*, by which the pointers or indicators *d'*, *d²*, etc., are driven in relation 65 to the dials which are depicted in the usual manner on the enameled dial plate *e*. The clock train *c* comprises as usual a primary shaft *c'*, through which motion is imparted to the clock train from the source of movement, secondary shafts *c²*, *c³*, etc., and co-operating gears and pinions *c⁵*. Each of the shafts *c'*, *c²*, etc., carries a corresponding pointer *d'*, *d²*, etc. The clock train is supported between parallel plates *f* and *g* which 70 are held in spaced relation by the devices to be described. As shown, posts *h*, shouldered at each end, are riveted into one of the plates, as *g*, and at the other end are extended slightly beyond the plate *f* and 75 headed, as at *h'*, to receive a slotted disk-like friction clip *i*. By these devices the two plates *f* and *g* are held securely in 80 spaced relation without the use of screws.

The primary shaft *c'* is mounted in elongated bushings, of any suitable material, such as hard rubber, fitted snugly in the plates *f* and *g*. The several shafts *c'*, *c²*, etc., are mounted in bushings in the two plates *f* and *g* in the same manner and the 85 bushings are retained in place in the two plates *f* and *g* in the same manner, so that 90 illustration of the relation of the bushings to one of the plates, as *f*, and of the means for retaining the bushings in place in that 95 plate, will suffice for both. Therefore only the elongated bushing *f'* in the plate *f* is shown. Each plate, as *f*, is formed with a seat, as at *f²*, to receive a bushing, as *f³*, of any suitable material, such as hard rubber, 100 the seat being counter-sunk so that the bushing can be introduced or removed from one side only.

To retain all of the bushings *f³* in their respective seats *f²*, the bushings are covered, 105 on the open side of the seats, by an annular plate *k*, which is conveniently interlocked with the plate *f*, as by means of bent prongs

k', struck up from the annular plate *k* and adapted to enter elongated slots *f*⁴ formed in the plate *f*, the slots being elongated in parallelism and the prongs also standing in parallelism. The annular plate is slightly domed, as at *k*², to give clearance over the end of the corresponding shaft of the clock train. The elongated bushing *f'* is preferably slightly flanged and is extended through both plates *f* and *k* when they are in working relation.

The enameled dial plate *e* is centered on the plate *g* by pins *g'* which are fixed in the plate *g* and pass through holes formed in the plate *e* before it is enameled and the dial plate is then held loosely in place by the pointers *d'*, *d*², etc. which are secured to the respective shafts *c'*, *c*² etc.

In assembling the clock train the bushings *f*³ are first placed in the seats *f*² prepared therefor in the respective plates *f* and *g*. The several shafts *c'*, *c*², etc. with their respective gears *c*⁵ are then placed in the bushings of one of the plates, as *g*, which is held with the countersunk seats *f*² uppermost, the annular locking plate *k*³ having been placed in position as hereinafter described with respect to the locking plate *k*. The frame plate *f* is then placed in position on the posts *h*, its bushings *f*³ receiving the ends of the shafts *c*², *c*³, etc. The locking plate *k* is then applied, with its prongs or fingers *k'* entering the slots of the plate *f* and is pushed to one side to cause the prongs or fingers to engage the plate *f*. The elongated bushing *f'* is then pressed into the registering openings formed therefor in the plates *f* and *k*, thereby preventing the slipping back of the locking plate *k*. It will be understood that the manner of applying the locking plate *k*³ to the plate *g* is the same as that already described with respect to the locking plate *k*, the locking plate *k*³, of course, being slotted

or provided with apertures, as at *k*⁴, to receive the several shafts.

I claim as my invention:

1. In a register, the combination of a clock train, a supporting frame having spaced supporting plates, one of such plates having counter-sunk recesses and elongated slots, 50 bushings in the seats of the supporting plate, and a locking plate to cover and retain the bushings in their seats and having prongs to enter the slots of the supporting plate and engage the supporting plate. 55

2. In a register, the combination of a clock train, a supporting frame having spaced supporting plates, one of such plates having counter-sunk recesses and elongated slots, 60 bushings in the seats of the supporting plate, a locking plate to cover and retain the bushings in their seats and having prongs to enter the slots of the supporting plate and engage the supporting plate, and means to prevent the locking plate from being slipped 65 back to disengage the prongs from the supporting plate.

3. In a register, the combination of a clock train, a supporting frame having spaced supporting plates, one of such plates having 70 counter-sunk recesses and elongated slots, bushings in the seats of the supporting plate, a locking plate to cover and retain the bushings in their seats and having prongs to enter the slots of the supporting plate and engage the supporting plate, and an elongated bushing to receive one of the shafts of the clock train, such elongated bushing entering registering openings in the supporting plate and in the locking plate to prevent the locking plate from being slipped back to disengage the prongs from the supporting plate. 75 80

This specification signed this 26 day of August A. D. 1920.

WILLIAM L. MARDEN.
